PORTRABLE RECORDER

Raymond B. Larsen, 103 E. Sunset,
Riverton, Wyo. 82501

Filed Aug. 26, 1965, Ser. No. 86,734

Term of patent 14 years

(Cl. D26—14)

I claim:

The ornamental design for a portable recorder, as shown.
